FUSED PLUG CONNECTOR

Watford C. Whitaker, Arcadia, Calif.

Application June 29, 1951, Serial No. 234,209

1 Claim. (Cl. 200—115.5)

1

This invention relates to an electrical apparatus and more especially to a fusible electrical plug and receptacle.

An object of the invention is to provide a simple, practical and inexpensive combination plug and receptacle having fuse features.

Another object of the invention is to provide a fused plug and receptacle having a novel form of replaceable fuse element.

An additional object of the invention is to provide a new plug and receptacle for electrical appliances so constructed as to occupy a minimum of space when in use.

Other objects and advantages will appear and be brought out more fully in the following specification, reference being had to the accompanying drawing.

In the drawing:

Figure 1 is a perspective view of a fused plug and receptacle embodying the invention.

Figure 2 is a sectional view taken along the line 2—2 of Figure 1.

Figure 3 is an exploded view of the fuse and terminal elements associated therewith.

Referring more particularly to the drawing, the numeral 10 designates generally a combination plug and receptacle having a body 11 of any suitable dielectric material, for instance, plastic and having flat faces 12 and 13, respectively, disposed at right angles to each other.

The body 11 is formed with elongated cavities 14 and 15 extending inwardly from face 12 and having slots 16 and 17 leading from the outer ends of the cavities and opening through face 12. The body is also formed with a slot 18 leading from cavity 14 and opening through face 13 and a tubular cavity 19 communicates with and leading from the inner end of cavity 15 and opening through face 13. Cavity 19 has an enlarged portion 20 adjacent to face 13.

Cavities 14 and 15 provide seats for female electrical receptacle electrodes 21 and 22 having plug receiving portions aligned with slots 16 and 17 and a plug electrode 23 is positioned in slot 18 and is suitably connected to the receptacle electrode 14.

A flexible and resilient conductor tongue 24 extends from the receptacle electrode 22 and has its inner end portion disposed across the tubular cavity 19. A sleeve 25 is tight fitted within bore 20 and has one or more bayonet slots 26. A plug electrode 27 has a cylindrical end portion 28 adapted to fit within sleeve 25 and carries one or more radially extending pins 29 for engagement in the bayonet slots 26 of sleeve 25. A

2

fuse 30 is positioned in cavity 19 and makes electrical contacts between end 28 of plug electrode 27 and the free end of tongue 24 carried by the receptacle electrode 22. The resiliency of tongue 24 retains fuse 30 in firm contact with end portion 28 of plug electrode 27. The arrangement of bayonet slots 26 and pins 29 is such that when the pin and slot engagement has been effected, the flat faces of plug electrodes 23 and 27 will be in parallelism properly for reciprocal engagement.

In operation the plug electrodes may be plugged into any conventional receptacle and the receptacle portion of the invention, that is, receptacle electrodes 21 and 22 may receive the conventional appliance plug. In the event of an overload occurring in the appliance circuit causing blowing of the fuse, the fuse 30 may be removed by a quarter turn of plug electrode 27, which releases the end portion 28 thereof from the sleeve 25 and permits the removal and replacement of the fuse. It will be observed that when the plug and receptacle 10 is connected in a wall receptacle, face 13 will be adjacent to the wall and the receptacle electrodes 21 and 22 will be directed at right angles to plug electrodes 23 and 27, so that plug electrodes of an appliance plug, engaging in the receptacle electrodes 21 and 22, will have its cord leading from the receptacle 30 generally parallel to the wall and therefore a minimum of space is occupied by the plug and receptacle of this invention.

It will be seen upon reference to Figure 2, that in the structure of the present invention 35 the resilient current conductor tongue 24, in addition to functioning as a current conducting means between the receptacle electrode 22 and the plug electrode 27, also functions as a yieldable means for maintaining the cylindrical inner end portion 28 of the plug electrode 27 tightly in position after the pins 29 have been engaged in the bayonet slots 26. It will be apparent that in the insertion of the end portion 28, such end portion must first force the fuse element 30 inwardly against the resilient conductor tongue 24 to bend and place the latter under spring tension. After the pins 29 are in position for engagement in the short end portions of the bayonet slots 26 the spring tongue 24 will shift the fuse 30 and the plug electrode 27 outwardly to lock the bayonet slot pins in the slots and since the distance between the inner end 28 of the plug electrode 27 and the spring tongue 24 is then less than the length of the fuse element, the spring tongue 24 will be maintained under

tension to hold the parts securely against movement.

While in the foregoing there has been shown and described the preferred form of this invention, it is to be understood that minor changes in the details of construction, combination and arrangement of parts may be resorted to without departing from the spirit and scope of the invention as claimed.

I claim:

In an electric plug connector, a body of an insulating material having a pair of elongated parallel cavities within the same and communicating with slotted apertures opening through an end face thereof, one of said cavities having a greater depth than that of the other cavity, resilient contact elements housed within said cavities, said body also having a tubular bore extending laterally outward from the inner end of said one cavity and opening through a side face of the body, a 20 resilient tongue extending from the contact element within said one cavity and having its free end disposed across the inner end of said bore, said bore being adapted to receive a fuse element therein with the inner end of the element disposed in contact with said tongue, said body having a counter-bore in the said side face in

concentric relation with respect to the first bore, a metallic sleeve provided with a bayonet slot tight fitted within said counter-bore, a plug electrode projecting laterally outward through said side face from the inner end of the contact element within said other cavity, a second plug electrode, a cylindrical enlargement at the inner end of said second electrode seated in said sleeve and against the outer end of the fuse element, and a pin projecting radially from said enlargement for engagement with said bayonet slot to effect the locking of said enlargement and the associated electrode in place.
